UNITED STATES PATENT OFFICE.

VIRGINIUS Z. CARACRISTI, OF BRONXVILLE, NEW YORK.

BOILER.

Application filed September 2, 1919. Serial No. 321,019.

To all whom it may concern:

Be it known that I, VIRGINIUS Z. CARACRISTI, a citizen of the United States, and resident of Bronxville, county of Westchester, and State of New York, have invented certain new and useful Improvements in Boilers, of which the following is a specification.

This invention relates to steam boilers and 10 more particularly to water tube boilers, and has for its object to provide an improved circulatory system for the water whereby it is heated and converted into steam, both by radiation within the furnace chamber 15 and by the heat of convection as the products of combustion pass through said chamber.

It is another object of my invention to 20 provide an improved arrangement of the water tubes, the headers and the mud drum with respect to the furnace structure whereby the heat units of the products of combustion will be fully utilized, resulting in the maintenance of a high boiler capacity.

25 It is also an important object of the invention to provide a novel arrangement of the water tubes in a plurality of banks or groups, whereby a maximum degree of circulating efficiency may be attained in the operation of the boiler.

With the above and other objects in view, the invention consists in the improved construction, combination and relative arrangement of the several parts, as will be herein- 35 after more fully described, illustrated in the accompanying drawings, and subsequently incorporated in the subjoined claims.

In the drawings wherein I have illustrated several practical embodiments of my 40 invention, and in which similar reference characters designate corresponding parts throughout the several views.

Fig. 1 is a vertical section through the boiler showing one embodiment of the invention;

Fig. 2 is a similar view illustrating an alternative construction; and

Figs. 3 and 4 are vertical sectional views 50 disclosing further embodiments of my invention.

Referring in detail to the drawings, and more particularly to Fig. 1 thereof, 5 generally designates the furnace structure having a chamber 6 through which the smoke 55 and products of combustion rise from the

fire box through the passage 7 which is laterally offset to one side of the center of the furnace structure.

In the opposite side walls of the furnace structure 5, and at relatively different elevations, the flat or rectangular headers 8 are arranged and suitably secured. These headers are connected to each other at their upper portions by a bank of water tubes 9 which are obliquely inclined across the furnace chamber 6 as shown.

A mud drum 10 is suitably mounted in the bottom wall of the chamber 6, and this drum is connected to the headers by the banks of vertical water tubes designated 11 70 and 12 respectively. The tubes 11 at their upper ends and below the bank of transverse tubes 9, are laterally extended in an outward direction and connected to one of the headers 8. The other bank of tubes 12 75 which are relatively short are also laterally extended below the transverse tubes 9 and are connected to the other of the headers 8.

A water feed drum 13 is mounted in one 80 side of the furnace structure at the upper end thereof, and is connected by a plurality of tubes 14 to the upper end of one header 8. A drum 15 is also mounted in the opposite side of the furnace structure and connected by tubes 16 to the other of the headers. 85 These drums 13 and 15 are connected to each other by a plurality of horizontal tubes 17 extending transversely of the furnace structure. 18 designates the steam receiving drum arranged above the drum 15 and connected thereto by the tubes 19. A plurality of downwardly inclined transverse tubes 20 connect the drum 18 to the feed drum 13.

A vertically disposed baffle wall 21 extends in parallel relation to the vertical portions of the tubes 11, said baffle wall contacting at its lower end with the wall of the mud drum 10. At its upper end this baffle follows the curvature of the upper ends of the tubes 11 for a short distance and is then 100 vertically extended as at 22 to a point above the bank of transversely inclined tubes 9.

A second baffle wall 23 is arranged in parallel relation to the vertical series of tubes 12 and has its lower end spaced from the mud drum 10. This baffle wall also extends above the tubes 9 and likewise above the horizontal tubes 17, and in effect, constitutes a continuation of the wall of the outlet stack 24 for the products of 110

combustion. By the provision of these baffle walls 21 and 23, it will be seen that an intermediate vertical passage 25 is provided through which the products of combustion must pass into the passage or chamber 26 between the baffle wall 23 and the adjacent side wall of the furnace. Above the header 8, this furnace wall is provided with an outlet 27. The stack 24 is equipped with a suitable damper 28 so that the passage through this stack may be closed to any desired extent and thereby cause a greater or less proportion of the products of combustion to enter the outlet 27.

As I have indicated in the drawings in dotted lines, a superheater 29 may be arranged above the upper end 22 of the baffle wall 21, and below the horizontal water tubes 17, or a superheater 30 may be arranged in the passage 25 between the baffle walls 21 and 23. By the provision of the flat headers 8, access may be easily had to the several water circulating tubes from the exterior of the headers, for the purpose of cleaning said tubes.

In the operation of the boiler, the water from the feed drum 13 flows downwardly through tubes 14 into the header 8, a portion of the water passing through the bank of tubes 9 to the opposite header, while the remainder flows downwardly through the tubes 12 and enters the mud drum 10. From this drum, the water rises through the other bank of tubes 11 to the opposite header 8 and hence passes upwardly into the drum 16. The water during its flow through the two vertical banks of tubes 11 and 12, is heated by radiation of heat from the products of combustion passing upwardly through the furnace chamber. The products of combustion then impinge against the individual tubes 9 extending transversely across the upper end of the furnace chamber so that the water is also heated and converted into steam by the heat of convection. The steam flows upwardly from the drum 15 into the drum 18 from which it is withdrawn through the pipe 31 and either conducted directly to the point of utilization or to the superheater. It will be readily seen that by the provision of the transverse bank of tubes 9 in addition to the vertical banks of tubes 11 and 12, there is obtained a maximum number of water passages upon the walls of which the products of combustion will impinge in their passage to the outlet stack or flue. By arranging the superheaters as indicated, it is possible to maintain a high degree of operating efficiency and secure a maximum temperature of the steam.

In Fig. 2 of the drawings I have illustrated a slightly different construction wherein the mud drum 10' is located at one side of the furnace structure and in line

with one of the headers 8. In this arrangement, in addition to the inclined transverse tubes 9, a series of vertical tubes 12' connect the mud drum 10' to the header which is in line therewith, while a series of relatively long curved tubes 11' connect the opposite header 8 to the mud drum. The baffle walls 23' and 21' corresponding to those above referred to are also provided in this arrangement of the boiler tubes. The relatively long curved tubes 11' are heated substantially throughout their length by the products of combustion, and provide a very economical installation, while affording an extensive heat conducting area. In this arrangement likewise, it will be readily seen that the water is heated and converted into steam in its passage through the tubes 11', 12' and 9, first by the heat of radiation, and secondly by the heat of convection.

In Fig. 3 of the drawings I have disclosed another arrangement in which the mud drum 10' is centrally arranged as in Fig. 1. The headers 32 and 33 are arranged in opposite sides of the furnace structure and at different elevations. In this form of the boiler, the headers are cylindrical, and the header 33 is of greater diameter than the header 32. This header 33 is connected to the water feed drum 13' by the horizontal tubes 17' and to the steam collecting drum 18' by the vertical tubes 19'. Downwardly inclined tubes 20' connect the steam collecting drum 18' to the water feed drum 13'.

In the construction disclosed in Fig. 3, a bank of transversely inclined tubes 9' connect the header drums 32 and 33 with each other, and a second bank of water tubes 11' and 12' extends downwardly from each of the header drums, said tubes likewise being obliquely inclined in an inward direction and connected at their lower ends to the mud drum 10'. Water conducting tubes 14' connect the water feed drum 13' to the header 32, and immediately below this header, the furnace structure is provided with the outlet 27' for the products of combustion. The baffle wall 21' extends upwardly from the mud drum 10' and for about one half the length of the tubes 11' and is then inwardly and obliquely inclined and extended upwardly across the bank of tubes 9' as shown at 22'. The other baffle wall 23' which corresponds to the baffle wall 23 above referred to, has its lower portion inclined inwardly and terminating at its lower end in spaced relation to the drum 10'. This arrangement likewise affords a boiler having a maximum steam generating capacity.

In Fig. 4 I have illustrated a duplex water tube boiler in which the arrangement shown in Fig. 3 is duplicated. In this case,

the mud drums 10^b are arranged respectively in the opposite sides of the furnace structure, while the header drums 33^b are arranged centrally of the furnace at the top 5 thereof, and connected to each other by a series of tubes 34. The steam collecting drum 18^b is connected by two series of tubes 19^b to the respective header drums 33^b, and the tubes 20^b extend from the opposite sides 10 of the collecting drum to the respective water feed drums 13^b. In this double boiler arrangement, it will be understood that the products of combustion rise through the center of the furnace chamber, and after 15 impinging upon the two series of water tubes 11^a, strike the top wall of the furnace chamber and then pass downwardly between the spaced baffle walls and finally upwardly through the bank of tubes 12^a at each side of 20 the furnace to the outlet stack or flue. It will be appreciated that by means of this novel arrangement of the banks of water circulating tubes, in the double boiler construction, of comparatively small size, I obtain a very 25 high ratio between the heating surface of the drums and the heating surface of the tubes whereby the fuel consumption is materially reduced.

It is of course possible to arrange the 30 several series of water circulating tubes in numerous other ways than as suggested in the accompanying drawings without departing from the salient features of my invention, namely, the provision of a transversely extending bank of tubes connecting the headers to each other above the two vertical series of water tubes, and the relative arrangement of the baffles so as to obtain a maximum heating effect on the water circulating 35 through said tubes during the passage of the products of combustion through the furnace chamber. It is a well known fact, that the heat of convection is more effective in the operation of 40 water tube boilers in converting the water into steam, than a radiant heat. In each of the above disclosed embodiments of my invention, I have succeeded in a very compact arrangement of the water tubes in effectively utilizing the initial radiant heat as 45 the products of combustion pass through the furnace chamber and travel in parallel relation to the vertical series of tubes, and then heating the water by convection as the 50 products of combustion finally pass through the transverse bank of tubes and impinge upon the individual tubes thereof before passing to the outlet stack of the furnace. It is accordingly to be borne in mind that 55 while I have herein disclosed several practical constructions, the invention may likewise be exemplified in numerous other alternative forms, and I therefore reserve the privilege of adopting all such legitimate 60 changes in the form, construction and rela-

tive arrangement of the several parts as may be fairly embodied within the spirit and scope of the invention as claimed.

I claim:

1. In combination with a furnace structure, a water tube boiler including headers mounted in opposite sides of the furnace structure, a mud drum mounted in the lower end of the furnace structure, a bank of water circulating tubes connecting each 70 of the headers to the mud drum, water and steam drums mounted in the furnace above the headers, means separate from said water circulating tubes for establishing water connection between the headers through said drums so as to provide a complete system of water circulation in the furnace, an additional bank of water circulating tubes connecting the headers to each other 75 and extending across the furnace above said first bank of tubes, and baffles subdividing the furnace chamber into a plurality of intercommunicating passages for the products of combustion and permitting of the unimpeded normal travel of the gases along 80 and between the tubes in the first mentioned bank and the repeated impingement of the gases upon the tubes in said additional bank. 85

2. In combination with a furnace structure, a water tube boiler including a pair of headers, spaced banks of vertically extending water circulating tubes connected to the respective headers at one of their ends and communicating with each other at their other ends, a longitudinally disposed bank of water circulating tubes connecting the headers with each other above said spaced banks of vertical tubes, additional means separate from said tubes and including a water drum for conducting water from one to the other of said headers, and spaced baffle walls sub-dividing the furnace chamber into a plurality of intercommunicating vertical passages, said baffle walls extending in parallel relation to the vertical banks of tubes and also across the longitudinal bank of tubes at spaced points along the latter tubes to thereby concentrate the products of combustion and cause their impingement successively upon different portions of said longitudinal tubes while permitting of the unimpeded flow of such products of combustion through the 100 passages to the furnace. 105

3. In combination with a furnace structure, a vertical type water tube boiler including rectangular headers mounted in the opposite side walls of the furnace structure, a mud drum mounted in the lower part 110 of the furnace structure, spaced vertically extending banks of water circulating tubes connecting the respective headers to the mud drum, a longitudinally inclined bank 115 of water circulating tubes connecting the 120 mud drum to the outlet stack of the furnace, and spaced baffle walls sub-dividing the furnace chamber into a plurality of intercommunicating vertical 125 passages, said baffle walls extending in parallel relation to the vertical banks of tubes and also across the longitudinal bank of tubes at spaced points along the latter tubes to thereby concentrate the products of combustion and cause their impingement successively upon different portions of said longitudinal tubes while permitting of the unimpeded flow of such products of combustion through the 130 passages to the furnace. 135

- headers to each other and arranged above said longitudinal banks of tubes, additional means separate from said tubes and including a water drum for conducting water 5 from one to the other of said headers, and spaced baffle walls extending in the same general direction as the respective banks of vertical tubes and also extending across the longitudinal bank of tubes at points 10 spaced longitudinally thereof, said baffle walls dividing the furnace chamber into a series of intercommunicating vertical passages permitting of the unretarded flow of the products of combustion through said 15 passages and concentrating the products of combustion for impingement upon the longitudinal bank of water tubes a plurality of times before passing into the outlet of the furnace.
- 20 4. In combination with a furnace structure, headers mounted in the opposite sides of said structure and at different elevations, a bank of longitudinally inclined water circulating tubes connecting the headers 25 to each other, a mud drum below the headers, additional banks of water circulating tubes connecting each of the headers to said drum and arranged substantially in parallel relation for a portion of their 30 length, spaced vertically disposed baffle plates disposed in parallel relation to the latter tubes and extending across the longitudinally inclined tubes to cause the products of combustion to travel in a circuitous 35 course through the furnace chamber and impinge upon all portions of the tubes in the several banks, a water feed drum connected to one of said headers, a steam collecting drum connected to the other headers, and a series of tubes connecting the steam collecting drum to the water feed 40 drum.
6. In combination with a furnace structure, a pair of headers mounted on opposite sides of the furnace, water and steam drums 45 mounted in the furnace above the headers, tubes connecting the water and steam drums to each other, tubes connecting one of said drums to one of the headers and the other of said drums to the other header, a mud 50 drum, banks of tubes extending vertically of the furnace and connecting each of the headers to the mud drum, such banks of tubes, the mud drum, the headers, the water and steam drums and the connecting 55 tubes therebetween forming a complete system of water circulation throughout the furnace, and a bank of tubes extending between said headers longitudinally of the furnace and providing a path of flow for 60 water between said headers in the same general direction with respect to the furnace structure as the flow through the vertical tubes.
- 40 5. In combination with a furnace structure, headers mounted in the opposite sides of said structure and at different elevations, a bank of longitudinally inclined water circulating tubes connecting the head- 65 ers to each other, a mud drum below the headers, additional banks of water circulating tubes connecting each of the headers to said drum and arranged substantially in parallel relation for a portion of their 70 length, spaced vertically disposed baffle plates disposed in parallel relation to the latter tubes and extending across the longitudinally inclined tubes, to cause the products of combustion to travel in a circuitous course through the furnace chamber and impinge upon all portions of the tubes in the several banks, a water feed drum connected to one of said headers, a steam collecting drum connected to the other headers, and a series of tubes connecting the steam collecting drum to the water feed 75 drum.
- In testimony that I claim the foregoing 80 as my invention, I have signed my name hereunder.

VIRGINIUS Z. CARACRISTI.
